US00D901071S

(12) **United States Design Patent** (10) **Patent No.:** **US D901,071 S**
Goradesky (45) **Date of Patent:** ** *Nov. 3, 2020

(54) **CONTAINER FOR ORGANIC SMOKING MATERIAL**

(71) Applicant: **Buddy Box, LLC**, Weston, FL (US)

(72) Inventor: **Harold Scot Goradesky**, Plantation, FL (US)

(73) Assignee: **Buddy Box, LLC**, Weston, FL (US)

(*) Notice: This patent is subject to a terminal disclaimer.

(**) Term: **15 Years**

(21) Appl. No.: **29/723,875**

(22) Filed: **Feb. 11, 2020**

Related U.S. Application Data

(63) Continuation of application No. 16/291,902, filed on Mar. 4, 2019, which is a continuation of application No. 16/130,609, filed on Sep. 13, 2018, now Pat. No. 10,258,081.
